UNITED STATES PATENT OFFICE

145,876

DESIGN FOR A LUMINOUS ASH TRAY

James Ross, Hubbard Woods, Ill.

Application October 20, 1944, Serial No. 115,891

Term of patent 3½ years

(Cl. D85—2)

To all whom it may concern:

Be it known that I, James Ross, a citizen of the United States, residing at Hubbard Woods, in the county of Cook and State of Illinois, have invented a new, original, and ornamental Design for a Luminous Ash Tray, of which the following is a specification, reference being had to the accompanying drawing, forming a part thereof.

Fig. I shows a top plan view of the luminous ash tray embodying my design.

Fig. II is a cross section taken on line 2—2 of Fig. I.

The characteristic feature of my design for ash tray resides in the surface ornamentation thereof as shown in the drawing.

I claim:

The ornamental design for a luminous ash tray, substantially as shown and described.

JAMES ROSS.
